UNITED STATES PATENT OFFICE.

FRANK E. WELLMAN, OF KANSAS CITY, KANSAS.

MANUFACTURE OF GASOLENE.

1,362,160.

Specification of Letters Patent. Patented Dec. 14, 1920.

Application filed June 24, 1919. Serial No. 306,321.

To all whom it may concern:

Be it known that I, FRANK E. WELLMAN, a citizen of the United States, residing at Kansas City, in the county of Wyandotte and State of Kansas, have invented certain new and useful Improvements in the Manufacture of Gasolene, of which the following is a specification, reference being had therein to the accompanying drawing.

10 My invention relates to the treatment of hydrocarbons for the purpose of producing from such hydrocarbons of relatively high boiling points, other hydrocarbons of much lower boiling points, such as the commercial product known as gasolene or motor fuel which is in the paraffin series.

My process to be specifically described hereinafter, is an improvement primarily over that disclosed in the Leffer French Patent No. 439,476, issued June 14, 1912. Incidentally it involves certain changes and improvements which fall generally in the same class as those described in U. S. patents to Burton, No. 1,049,667, January 7, 1913, 25 and Humphreys, No. 1,119,700, December 1, 1914. The manner in which my process differentiates from the Burton and Humphreys processes, will be evident from the detailed description.

30 Generally stated, my process is one of re-cracking, with reflux condensation, some initial condensation under pressure, and a separate final release and condensation or cooling of the heavier products which have been cracked. I make no claim, broadly, to either reflux condensation or re-cracking, as these were both old in the art before the date of the French patent hereinbefore referred to.

40 Neither do I claim, broadly, the ideas of regulating temperatures or pressures or both.

The problems presented are solved by my present process, by causing pressure to be restrained effectively between the cracking still and the initial condenser without mechanical moving parts, and also by maintaining pressure by means of an inert gas such as nitrogen, or the gases remaining upon the new charge of oil when it is placed in the cracking still. Autogenous pressure of course does not begin to operate so as to raise the operative pressure in the still, until the lighter vapors are driven off by heat.

55 It is during this period of initial heating that fixed gases and very light condensable

products are given off in greatest volume, due to the lack of chemical equilibrium. Among the lighter products in the paraffin series which must be permitted from the outset, are those within the limiting range of so-called "gasolene" which in this, as in other cracking processes, is the principal product sought. I first charge my cracking still under pressure of an inert gas or gases, as above, then close the inlet pipe, both for oil and air, and subject the charge to high temperature. The initial pressure is sufficient to balance the gas pressure for the initial temperature, and the initial product is separately removed, preferably through means which save heat and avoid mechanical losses, and condensed. This initial product is known around the refineries as "benzin" or "crude gasolene." It differs in my present process in no wise from the usual "natural run" of gasolene which is usually taken off at the beginning of the Rittman and other well known processes, but owing to my use of the principle of pressure by inert gas, it is more copious in yield because of the balance or equilibrium which prevents or checks the formation of fixed gas. After passing off this initial yield, and as the temperature rises, I provide for continued cracking, with constant reflux.

While the reflux and re-cracking part of my process is proceeding I continue to carry off the gasolene yield, which is condensed by itself. After this slackens, the contents of the cracking still are bodily discharged by means of their own pressure, and the contents separately cooled and condensed, after which, as an ancillary feature, I may scour out the still with superheated steam under high pressure, before re-charging. The condensate blown out is in the aggregate lighter than the body of the original charge, and may be further treated to extract its lighter constituents.

In carrying out my process I make use of certain apparatus which I have designed for that purpose, which may be briefly described as follows:

A horizontal cracking tube is employed, with a pressure discharge valve at one end leading to a receiving tank, through a cooling coil. This valve is closed until the end of the operation. From the top of the tube rises an inclined run-back which for various reasons is made large. From this run-back or reflux chamber a gasolene pipe is taken

off to an ordinary condenser. To the same run-back a feed pipe for charging oil under pressure of an inert gas or gases, such as nitrogen, is connected, as also a steam pipe 5 for scouring.

I shall claim the separate discharge means in combination with the other parts of this system, *i. e.*, to the gasoline pipe and condenser on the one hand, and the blow-out 10 discharge on the other. While separate discharge pipes for the same still are broadly old, they have never, to my knowledge, been used in such a system as this, nor for my purpose.

15 My invention is illustrated in the accompanying drawings in which—

Figure 1 is a diagram showing a complete system, and

20 Fig. 2 is a similar diagram showing a low pressure condenser and its connections.

Referring to Fig. 1, the apparatus consists of a horizontal cracking tube or retort 1, which is 20 feet long and 8 inches in diameter, from which, toward one end, extends 25 upwardly at an angle of about 30 degrees a fractionator tube or reflux pipe 4, which is supposed to have about the same diameter and cubical capacity as the horizontal or cracking retort. In one successful example 30 this tube was 27 feet by 10 inches in diameter. From the upper end of this sloping pipe a one-half inch gasoline line 7 extends for the most part horizontally to a condensing worm, beyond which is a pressure-regulating valve 11, followed by a tank 12 for 35 the collection of light distillates. A valved steam line 6 enters the upper end of the sloping pipe 4; and a valved pipe 5 for charging fresh oil enters the same pipe some 40 little distance from its upper end. The end of the horizontal cracking retort 1 farthest away from the sloping pipe 4 discharges through a valved outlet 15—16 into a cooling coil 17 and thence into a storage tank 18.

45 The horizontal tube 1 is filled substantially full of the oil to be cracked. All valves shown in the drawings are closed with the exception of the pressure regulating valve 11 beyond the light distillate condenser. The oil is heated to about 850° F. according to the notation on the drawing; but the operating temperature is usually in excess of 850° F. The pressure-regulating or throttling valve is set to give an autogenous pressure in the vapor space provided by the sloping pipe of from 100 to 150 pounds, the degree of pressure used in any particular instance depending upon the pressure necessary to prevent vaporization of the heavier 55 oils. Under these conditions, the oil vapors generated fill the sloping fractionator tube 4, and such as are not condensed therein pass out through the gasoline line 7 and are condensed under pressure in the worm 8, any 60 accompanying fixed gases being allowed to

escape in the usual way. A certain proportion of the heavier vapors condenses in the fractionator tube 4 and refluxes to the horizontal tube 1 for further cracking. As shown, no special cooling means for the fractionator or reflux tube is used, simple air cooling being relied upon.

The distillation is continued until somewhat less than two-thirds of the batch is distilled off. At this point, the discharge 75 valve 16 at the end of the horizontal cracking tube 1 is opened and the residue is automatically blown out through the cooling coil 17 into the storage tank 18. From the residue a small percentage of gasoline may 80 be obtained by straight distillation.

After the heavy residuum has been blown out of the cracking tube, high pressure steam is admitted through the inlet 6 at the upper 85 end of the reflux tube 4 and the entire apparatus is thoroughly flushed out to remove carbon deposits, etc. A fresh charge of oil is then introduced, and the operations already described are repeated.

The cracking tube 1 may have welded 90 heads, but it is shown with bolted heads 2 and 3. The cooling coil 17 must be of large diameter and the valve 16 is preferably included in that portion within the cooling water or else provided with special cooling 95 means. The tank 18 may be provided with any desired form of relief valve set to blow off at a proper pressure.

Referring to Fig. 2, the parts are the same in their general arrangement, the horizontal 100 cracking tube, the inclined vapor chamber and the gasoline line leading to the condenser being employed as before. The choking effect of this benzene line which as stated is preferably of $\frac{1}{2}$ inch pipe is enhanced by including in its length a coil or worm 20, in a closed tank 21 having an oil charging pipe 22 through which oil may be pumped or otherwise forced into the tank, an air pipe 23 through which a neutral 105 agency as air under pressure may be pumped in to produce constant pressure on the oil, and a discharge pipe 24 leading to the charging or inlet pipe 5 of the vapor chamber and cracking tube. In this case the condenser or worm 8 is made of pipe of large diameter relatively to the gasoline line 7, whereby vapors leaving the latter will expand into the condenser and any pressure remaining will be lost as they condense on 110 the cool walls of the worm. Obviously this worm may be replaced by a dephlegmator or a cylindrical condenser, or any other desired form of cooling chamber, provided the volume of content is large enough to permit 115 expansion from the pipe 7. In this case there is no necessity for a pressure regulating valve outside the condenser at all, and the only valves shown so located are the draw-off valve 25 of the receiving tank 12, 120 125 and the discharge valve 16 of the cracking tube 1.

and the safety valve or blow-off of the same which may be set at a low pressure or left open for the escape of the fixed gases. I find that by regulating the pressure at this 5 end to a point between zero and 50 pounds, I get better results, a better grade of motor fuel, and less scouring effect and depreciation in the apparatus than in the forms hereinbefore referred to as requiring valves. In 10 this sense my present apparatus and process are in the nature of an improvement over those described in the Burton and Humphreys patents, as well as over my own previous applications Serial No. 142,545, filed 15 Jan. 15, 1917 and Serial No. 168,223, filed May 12, 1917.

I desire it to be understood that a number of changes may be made in the apparatus described without departing from the invention, such as the use of any one of the throttling elements described without the others, or the substitution of equivalent parts which will produce the same result. It is of course necessary to maintain pressure 20 in the vapor chamber substantially equivalent to that in the cracking chamber, in order that the heavier fractions may circulate and be cracked by continued heating under pressure. This in itself is very old, 25 being shown in such patents as for example that to Laing 471,291, granted March 22, 1892, in which the pipe B performs the same function as my vapor chamber or reflux pipe 4, and the throttling effect is produced 30 by a loaded valve S instead of by the gasoline line. The pressure described by Laing is 80 pounds per square inch for operating on oil having a specific gravity of .970 which is of the same order, but somewhat higher 35 than the run of the oils, with which I have 40

successfully operated the present system which are downward (in gravity) of 38° B.

While I have shown and described herein only a single unit consisting of the cracking tube 1, vapor chamber 4, etc., it is to be understood that in practice I preferably use these in batteries, with such arrangements of valves and pipes as to effect economical as well as efficient transmission and condensation of the vapors. I have deemed it unnecessary to show such a battery in this application, the drawings being mere diagrams and the description restricted thereto for the sake of clearness and simplicity.

Having thus described my invention what I claim and desire to secure by Letters Patent is:

Apparatus of the class described comprising the following instrumentalities: a cracking chamber, a discharge pipe and a control- 60 valve for same, a supplemental elevated vapor chamber arranged to drain back heavy liquid fractions into the cracking chamber, a condenser, and a line of pipe connecting an elevated part of the vapor chamber with said condenser, said condenser being of such material, form and dimensions as to have a large capacity relatively to the delivery capacity of said pipe at high initial pressures and said pipe having a very small 65 capacity relatively to said vapor chamber whereby pressure will be automatically retained in said vapor chamber, and the vapors passing through the pipe under pressure from the vapor chamber will expand 70 into the condenser, and lose their pressure in so doing.

In testimony whereof I affix my signature.

FRANK E. WELLMAN.
